UNITED STATES PATENT OFFICE.

ADAM LOEFFELHOLZ AND ANTON PRIER, OF MILWAUKEE, WISCONSIN.

IMPROVEMENT IN LANTERNS.

Specification forming part of Letters Patent No. 137,223, dated March 25, 1873.

To all whom it may concern:

Be it known that we, ADAM LOEFFELHOLZ and ANTON PRIER, residing in Milwaukee, in the county of Milwaukee and State of Wisconsin, have invented a certain Improvement in Lanterns, of which the following is a specification:

This invention relates to a certain improvement in lanterns; and it consists of the combination, with the guard or fender rim, of a support or ring for the chimney, and of the general construction, combination, and arrangement of the constituent parts of the lantern, substantially as hereinafter more fully set forth.

In the annexed drawing, Figure 1 represents a vertical section of our improved lantern. Fig. 2 is a view in elevation of the lamp detached; Fig. 3, a horizontal section of Fig. 2 taken through the dotted line $x\ x$; Fig. 4, a side view of that part of the lamp upon which the chimney rests; Fig. 5, a horizontal section through the rim which receives the lower extremities of the wires or fenders of the lantern; and Fig. 6 is a vertical section through the upper end or part of the lantern taken from a point at a right angle to that at which Fig. 1 is taken.

Corresponding parts in the several figures are designated by similar letters of reference.

A refers to the lamp, upon the foot of which, soldered or otherwise suitably fastened thereto, is a vertical ring or wall, a , which, in consequence of its being isolated from the elevated or upper part of the lamp, forms a chamber, into which fits or enters the part B of the lamp. The said part performs the office of holding the lamp-chimney in place upon the lamp, and is supplied with lateral projections $b\ b$ both upon its lower and upper extremities, those upon its lower end entering open slots a^1 in the part or lamp-ring a , and held therein by next passing through openings a^4 in metallic springs or catches a^2 attached to the ring a . These spring-catches are inclosed by staples a^3 to prevent their being bent back too far when operated. Through this arrangement and construction of parts the lamp can be withdrawn without disturbing the chimney, which it is very often desirable to do—as when the lamp is to be filled with oil—an occurrence which takes place perhaps every two or three days. The projections upon the upper or overhanging portion of the part B en-

ter slotted openings $c\ c$ made in the rim C, into which the lower ends of the wires or fenders C' of the lantern enter. The said projections are fastened, after passing through the said rim C, by spring-catches $c^1\ c^1$ through openings c^2 , in which they pass. By means of this arrangement the chimney can be removed when it is desired to clean it or replace it by another in case of breakage. The cap or top D, the flanged rim of which receives the upper ends of the fenders C' braced by the circular wire C'', and which is properly perforated with ventilating-openings, is constructed with isolated female screw-threads $d\ d$ to receive male screw-threads $d^1\ d^1$ upon the exterior surface of the cylinder or cap D' fitting within said top D. The said cap D' constitutes the chimney-balance, and by means of the threads $d\ d^1$ it is rendered susceptible of vertical adjustment, by which it can be set or adjusted to suit chimneys of different lengths, and also caused to clamp them firmly down in place, its lower end coming down and fitting around the top of the chimney. The upper end of the said chimney-balance has inserted over it, at or about the center, a narrow bar or strip of tin or other incombustible material, d^2 , from each side or edge of which extends in an upward and inclined manner a deflector, d^3 . A handle, E, is attached to the lantern for making it susceptible for use.

Having thus described our invention, what we claim, and desire to secure by Letters Patent, is—

1. In combination with the rim C having the openings $c\ c$, and supplied with the spring-catch c^1 and fenders C' C'', the chimney-support B b with an overhanging flange, substantially as shown, and for the purpose described.

2. The lamp A a , chimney-support B $b\ b$, rim C $c\ c$ with spring-catch $c^1\ c^1$, fenders C' C'', cover D d , chimney-balance D' d^1 , and a chimney, all combined substantially as and for the purpose specified.

In testimony whereof we have hereunto signed our names this 9th day of December, A. D. 1872, in presence of two subscribing witnesses.

ADAM LOEFFELHOLZ.
ANTON PRIER.
